(57) **CLAIM**

I claim the ornamental design for bicycle chain bracelet, as shown and described.

DESCRIPTION

FIG. 1 is a perspective view of a bicycle chain bracelet showing my new design; latching closure in the closed position,

FIG. 2 is a top plan view thereof; and,

FIG. 3 is a side elevation view thereof.

1 Claim, 1 Drawing Sheet

FIG. 1

FIG. 2

FIG. 3
